His ATTORNEY.

UNITED STATES PATENT OFFICE

ANDREW J. SORENSEN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR ELECTRICAL CONTROL SYSTEMS

Application filed April 1, 1931. Serial No. 526,874.

My invention relates to apparatus for electrical control systems, and particularly for control systems making use of different code groups of current impulses.

5 I will describe one form of apparatus embodying my invention, and will then point out the novel features thereof in claims.

The present application is directed to an improvement on apparatus disclosed and 10 claimed in a copending application filed by Lars O. Grondahl, on April 4, 1930, Serial No. 441,593, for apparatus for the control of train brakes.

15 The accompanying drawing is a diagrammatic view illustrating one form of apparatus embodying my invention, when applied to a control system such as described and claimed in the copending application for United States Letters Patent of Lars O. Grondahl, 20 Serial No. 524,305, filed March 21, 1931, for apparatus for the control of vehicle brakes.

In control systems of the character disclosed in the above-mentioned application, 25 different control conditions are established by different code currents, each code being distinguished by groups of current impulses with each group containing a distinctive number of separate impulses, while each group of impulses is separated from the preceding and succeeding groups by a relatively long interval. When changing from one code to another in such systems, the completed portions of the first code taken either by itself or in combination with the second code 30 may constitute a third code, governing still another condition, and cause a momentary false operation. A feature of the present invention is to provide means for preventing the changing from one code to another during 35 the time of a code group of impulses.

40 While the form of the apparatus here disclosed is that for a control system where coded currents are transmitted by apparatus on a locomotive for governing the condition of an auxiliary brake controlling mechanism located on the train at another point, it will be understood that I do not limit myself to this specific type of control systems. My invention is equally adaptable to other control systems.

45 Referring to the drawing, the reference characters 1 and 1^a designate the traffic rails of a stretch of railway track in which a high frequency alternating current is at times produced by oscillator G, which is carried on a train, and which may be of any suitable type such, for example, as that disclosed in the copending Grondahl application above referred to. This oscillator supplies alternating current to a plurality of sending circuits, all of which include a pair of transmitting coils, 2 and 2^a, located in inductive relation with the track rails 1 and 1^a, respectively. These several sending circuits are controlled by a plurality of coding devices, 50 H¹, H², H³ and H⁴, respectively. Each of these coding devices consists of a constantly rotating cam 3 having a predetermined number of suitably spaced cam lobes 4, which are adapted to periodically close a contact 5—5^a in the associated sending circuit. The several cams are to be mounted on a shaft indicated by a dotted line, and which is to be driven by any convenient source of power not shown, such as a motor. These cams are 55 driven at a uniform speed to rotate in the direction indicated by the arrows. The cam lobes 4 of each coding device are positioned on the same respective portion of the circumference of the associated cam. As shown 60 in the drawing, they are positioned in the upper one-half of the circumference of the cams. Thus, in each case, as the cams rotate from the position shown in the drawing, the cam lobes of each coding device will intermittently engage the associated contact member 5 to close its associated contact 5—5^a 65 intermittently during the first one-half of a rotation. During the second one-half of a rotation, no cam lobes will engage a contact 70 75 80 85 90 95 100

rotate, each code consists of a predetermined group of current impulses which is separated from the preceding and succeeding groups by a relatively long interval.

5 The several sending circuits are also controlled by a plurality of relays F^1 , F^2 , F^3 and F^4 each having a pick-up winding 6 and a stick winding 7 and each in turn controlled by the engineer's brake valve lever indicated 10 by the reference character V.

The valve lever V is capable of occupying several positions C, R, L, S and E in which it controls respectively, the "release", "running", "lap", "service" and "emergency" condition 15 of the brakes. The lever V carries a contact member 8 which is adapted to engage an arcuate contact 9 in all positions of the lever V and also to engage a series of contacts 10, 11, 12 and 13 when the lever V 20 occupies its "release", "running", "lap" or "emergency" position, respectively.

The apparatus also includes a contact mechanism M which controls the pick-up circuits for all of the relays F, and a contact 25 mechanism K which controls the stick circuits for all of these relays. These contact mechanisms both operate in synchronism with the coding devices H and each comprise a rotatable disk 14 having a conducting portion 30 15 and an insulating portion 16 for alternate engagement with a spring contact finger 17. The conducting portion 15 and the insulating portion 16 each extend for substantially one-half of the circumference 35 of the disk, and the disks are angularly displaced relative to one another substantially 180° so that during one-half of a rotation of the disks the conducting portion of one is in engagement with its associated contact 17 40 and the insulated portion of the other is in engagement with its cooperating contact 17, and that during the other half of the rotation of the disks this condition is reversed. There is, however, a slight overlap of the 45 conducting portions 15 of the two disks so that at two points in their rotation the spring contacts 17 simultaneously engage the conducting portions of the disks.

In describing the operation of the apparatus, I will first assume that the engineer has placed the brake lever V at its release position C and that the coding devices H and contact mechanisms K and M, rotating in the direction indicated by the arrows, all occupy the 50 instantaneous positions shown in the drawing. With the parts in this condition, the relay F^1 is energized by virtue of a pick-up circuit passing from one terminal of a battery 18, through the contact members 9, 8 and 10, pick-up winding 6 of relay F^1 , and contact 55 17 and conducting portion 15 of contact mechanism M to the other terminal of battery 18. The energization of relay F^1 establishes a stick circuit for this relay passing from one terminal of battery 18, through the stick

winding 7 of relay F^1 , front contact 19 of this relay, back contacts 20, 21 and 22 of relays F^2 , F^3 and F^4 respectively, and contact 17 and conducting portion 15 of contact mechanism K to the other terminal of battery 18. 70

As soon as the rotation of the cam 3 of the coding device H¹ closes the associated contact 5-5^a, a circuit is established passing from one terminal of the oscillator G, through contact 5-5^a of coding device H¹, front contact 23 75 of relay F^1 , condenser 24, and transmitting coils 2 and 2^a to the other terminal of oscillator G. An alternating current is thus produced in the rails 1 and 1^a having the same frequency as that supplied by the oscillator G. Substantially simultaneously with the closing of the oscillator circuit just traced, the insulating portion 16 of the contact mechanism M moves into engagement with the associated contact 17 and opens the pick-up 80 circuit for relay F^1 , previously traced through this contact, but relay F^1 is maintained energized by the stick circuit controlled by a contact mechanism K. During the first one-half of a rotation of the coding device H¹ and contact disks 14, from the position shown in the drawing, the coding device H¹ periodically closes and opens its contact 5-5^a in the associated sending circuit, which 85 produces alternating current impulses in the track rails 1 and 1^a according to the code determined by the number and spacing of the cam lobes 4 of the coding device H¹. Throughout this first one-half rotation of the coding device H¹, the insulated portion 16 of the contact mechanism M, except for the brief period at the start, 90 is in engagement with the associated contact 17, and consequently, the pick-up circuit for the relay F^1 remains open at this point. However, the relay F^1 is retained energized by the stick circuit that is now closed at the front contact 19 and the contact 17 of the contact mechanism K which is now in engagement with its associated conducting 95 portion 15. 100

As soon, however, as the coding device H¹ completes its first one-half rotation from the position shown in the drawing, its code group of current impulses is completed and it ceases 115 to actuate its associated contact member 5 during the next one-half rotation. At the point where the code group is completed, the insulated portion 16 of the contact mechanism K moves into engagement with its contact 17 to open the stick circuit with the relay F^1 . Just before the stick circuit is opened the conducting portion 15 of the contact mechanism M moves into engagement with its contact 17, 120 and again closes the pick-up circuit, so that the relay F^1 is still retained energized during the second one-half rotation of the coding device H¹. The cycle of operation just described will be repeated as long as the brake valve lever V occupies its release position. 125

To sum up the operation thus far, during the first one-half rotation of the coding device H^1 , the stick circuit for the relay F^1 is closed, holding the relay energized, irrespective of the lever V , and a code group of impulses is supplied to the transmitting coils 2 and 2^a . During the second one-half rotation of the coding device H^1 , no code impulses are supplied, the stick circuit for the relay F^1 is open and the pick-up circuit is closed so that the relay F^1 is under the control of the lever V during this second one-half rotation. It follows that if the engineer should move the lever V to another position at any time during the first one-half rotation of the coding device H^1 , the relay F^1 associated therewith, remains energized permitting the completion of the code group of impulses.

Starting with the parts in the condition as shown in the drawing, and assuming that the engineer places the lever V at its running position R , the relay F^2 will become energized by virtue of a pick-up circuit passing from one terminal of battery 18 to contact members 9, 8 and 11, pick-up winding 6 of the relay F^2 , and contact mechanism M to the other terminal of the battery 18. Just before the first of the cam lobes 4 of the coding device H^2 closes its associated contact 5-5^a as the cams rotate from the position shown in the drawing, the conducting portion 15 of the contact mechanism K moves into engagement with its contact 17 and closes a stick circuit for the relay F^2 passing from one terminal of battery 18, through the stick winding 7 of relay F^2 , back contact 25 of relay F^1 , front contact 26 of relay F^2 , back contacts 27 and 28 of relays F^3 and F^4 , respectively, and contact mechanism K to the other terminal of battery 18. As soon as the rotation of the coding device H^2 closes the associated contact 5-5^a, a circuit is established passing from one terminal of the oscillator G, through contact 5-5^a of coding device H^2 , front contact 29 of relay F^2 , condenser 24 and transmitting coils 2 and 2^a to the other terminal of oscillator G. Alternating current impulses are thus produced in the rails 1 and 1^a according to a code determined by the coding device H^2 .

If the engineer had placed the valve lever V at its lap position L , relay F^3 would have become energized by virtue of a pick-up circuit passing from one terminal of battery 18, through contact members 9, 8 and 12, pick-up winding 6 of relay F^3 , and contact mechanism M to the other terminal of battery 18. With the coding device H^3 in the position in which it is shown in the drawing, that is, to say, just before the first of its cam lobes 4 closes its contact 5-5^a, the conducting portion 15 of the contact mechanism K moves into engagement with its contact 17 and completes a stick circuit for relay F^3 passing from

one terminal of battery 18, through stick winding 7 of relay F^3 , back contacts 30 and 31 of relays F^1 and F^2 , respectively, front contact 32 of relay F^3 , back contact 33 of relay F^4 , and contact mechanism K to the other terminal of battery 18. As soon as the rotation of the coding device H^3 closes its associated contact 5-5^a, a circuit is established passing from one terminal of the oscillator G, through contact 5-5^a of coding device H^3 , front contact 34 of relay F^3 , condenser 24 and transmitting coils 2 and 2^a to the other terminal of the oscillator G. Alternating current impulses are thus produced in the rails 1 and 1^a according to a code determined by the coding device H^3 .

If the engineer should move the valve lever V to its "emergency" position E , the relay F^4 , will, when contact mechanism M reaches the proper position, become energized by virtue of a pick-up circuit passing from one terminal of battery 18, through contact members 9, 8 and 13, pick-up winding 6 of relay F^4 , and contact mechanism M to the other terminal of battery 18. With coding device H^4 in the position in which it is shown in the drawing, that is to say, just before the first of its cam lobes 4 closes its contact 5-5^a, the conducting portion of the contact mechanism K engages its contact 17 and completes a stick circuit for relay F^4 passing from one terminal of battery 18, through stick winding 7 of relay F^4 , back contacts 35, 36 and 37 of relay F^1 , F^2 and F^3 , respectively, front contact 38 of relay F^4 , and contact mechanism K to the other terminal of the battery 18. As soon as the rotation of the coding device H^4 closes its associated contact 5-5^a, a circuit is established passing from one terminal of the oscillator G through contact 5-5^a of coding device H^4 , front contact 39 of relay F^4 , condenser 24, and the transmitting coils 2 and 2^a , to the opposite terminal of the oscillator G. Alternating current impulses are thus produced in the rails 1 and 1^a , according to a code determined by the coding device H^4 .

From the foregoing, it will be noted that the contact mechanism M controls the pick-up circuits of all the relays F jointly with the lever V and that the contact mechanism K controls the stick circuit of all the relays F independent of the lever V . Also that during the period a code group of current impulses is being supplied to the transmitting coils 2 and 2^a , the stick circuit is effective to energize the associated F relay and that during the long interval between code groups, the pick-up circuit is effective to energize the associated relays F . It follows, then, that if the lever V has been moved to a position in which it has caused the energization of one of the F relays in order to transmit a certain code, a subsequent movement of the lever V to another position will not cause the deenergi-

zation of such relays or the energization of the F relay associated with the new position of the lever V until the stick circuit for the first mentioned relay is opened, and this will 5 not occur until the code group of impulses is completed.

As stated earlier in the specifications, I do not wish to limit myself to the one type of control system here referred to, my invention 10 being equally adaptable to any system where a group of code impulses is supplied to a sending circuit. Such apparatus as here described provides full assurance that no false third code can be established by a portion of another 15 code, either when taken by itself or when combined with a portion of some other code.

Although I have herein shown and described only one form of apparatus embodying my invention, it is understood that various 20 changes and modifications may be made therein within the scope of the appended claims without departing from the spirit and scope of my invention.

Having thus described my invention, what 25 I claim is:

1. Apparatus for a control system including, a source of current, coding means adapted to code at recurrent intervals the current supplied by the source into a predetermined 30 group of current impulses, a relay for controlling the supply of said coded current to a sending circuit, a pick-up circuit and a holding circuit for said relay, manually operated means to control the pick-up circuit, and 35 contact mechanism operated in timed relation with the coding means arranged to close the pick-up circuit only during the time interval between two code groups of impulses and to close the holding circuit only during 40 the time interval of a code group and thereby automatically establishing the continuous repeating of the code group of impulses and preventing the manually operated means from energizing or deenergizing the relay 45 during a code group of impulses.

2. Apparatus for a control system including, coding means adapted to supply to a sending circuit a different coded current for each of a plurality of different conditions 50 with each code consisting of a distinctive group of current impulses, a plurality of relays each controlling one of said codes, a pick-up circuit and a holding circuit for each relay, manually operated means having 55 a different position for each of said different conditions to select the pick-up circuit for the corresponding relay, and contact mechanism operated in timed relation with the coding means arranged to close the selected pick-up 60 circuit only during the time interval between two code groups of impulses and to close the holding circuit for the selected relay only during the time interval of a code group of impulses and thereby automatically establish 65 the continuous repeating of the code cor-

responding to the selected relay and preventing a change in the position of the manually operated means effecting the energizing of a relay except during the interval between two code groups of impulses.

3. Apparatus for a train brake control system comprising in combination with the usual engineer's brake valve on the locomotive and an auxiliary brake controlling mechanism at another point on the train, coding means adapted to supply to the traffic rails at recurrent intervals a different coded current for each position of the engineer's brake valve for governing the auxiliary mechanism and with each code consisting of a distinctive group of current impulses, a plurality of relays each controlling one of said codes, a pick-up circuit and a stick circuit for each of said relays, contact means governed by the position of the engineer's valve to select the pick-up circuit for the corresponding relay, and a contact mechanism operated in timed relation with said coding means to alternately open and close the pick-up and stick circuits of the selected 90 relay and arranged to close the pick-up circuit and open the stick circuit during the interval between two code groups of impulses and to open the pick-up circuit and close the stick circuit during the interval of a code 95 group of impulses and thereby permit a change in the position of the engineer's valve to effect a change in the selection of the relays only at the end of a code group of impulses.

4. Apparatus for a train brake control system comprising in combination with the usual engineer's brake valve on the locomotive and an auxiliary brake controlling mechanism at another point on the train, coding means adapted to supply to the traffic rails at recurrent intervals a different coded current for each position of the engineer's brake valve for governing the auxiliary mechanism and with each code consisting of a distinctive group of current impulses, a plurality of relays each controlling one of said codes, a pick-up circuit for each relay controlled by a corresponding position of the engineer's valve, and a stick circuit for each relay including a back contact of each of the remaining relays in series to thereby prevent no two of said relays to be retained energized at the same time.

5. Apparatus for a train brake control system comprising in combination with the usual engineer's brake valve on the locomotive and an auxiliary brake controlling mechanism at another point on the train, coding means adapted to supply to the traffic rails at recurrent intervals a different coded current for each position of the engineer's brake valve for governing the auxiliary mechanism and with each code consisting of a distinctive group of current impulses, a plurality of re-

lays each controlling one of said codes, a pick-up circuit for each relay controlled jointly by a corresponding position of the engineer's valve and a contact operated in timed relation with the coding means and arranged to open said pick-up circuit during the interval of each code group of impulses, a stick circuit for each relay including a back contact of each of the remaining relays in series and a second contact operated in timed relation with the coding means arranged to close the stick circuit only during the interval of a code group of impulses, said pick-up and stick circuits thereby permitting the selecting of the relay corresponding to the position of the engineer's valve only during the interval between code groups of impulses and preventing any two of said relays to be retained energized at the same time.

20 6. Apparatus for a train brake control system comprising in combination with the usual engineer's brake valve on the locomotive and an auxiliary brake controlling mechanism at another point on the train, coding means adapted to supply to the traffic rails at recurrent intervals a different coded current for each position of the engineer's brake valve for governing the auxiliary mechanism and with each code consisting of a distinctive 25 group of current impulses, a plurality of relays each controlling one of said codes, an energizing circuit for each of said relays controlled jointly by the position of the engineer's valve and a contact operated in timed relation with the coding means and arranged to be closed only during the time interval between two code groups of impulses, a holding circuit for each of said relays including a second contact operated in timed relation 30 with the coding means and arranged to be closed during the time interval of a code group of impulses, said energizing and holding circuits of each relay thereby permitting the relay corresponding to the position of 35 the engineer's valve to be selected between two code groups of impulses and automatically establishing the continuous repeating of the code group corresponding to the relay selected as long as the engineer's valve remains in the one position.

40 7. Apparatus for a train brake control system comprising in combination with the usual engineer's brake valve on the locomotive and an auxiliary brake controlling mechanism at another point on the train, coding means adapted to supply to the traffic rails at recurrent intervals a different coded current for each position of the engineer's brake valve for governing the auxiliary mechanism and with each code consisting of a distinctive 45 group of current impulses, a plurality of relays each controlling one of said codes, a pick-up circuit for each relay controlled jointly by a corresponding position of the engineer's valve and a contact operated in timed rela-

tion with the coding means and arranged to close said pick-up circuit only during the time interval between two code groups of impulses, a stick circuit for each relay including a second contact operated in timed relation with the coding means arranged to close the stick circuit only during the time interval of a code group of impulses, said pick-up and stick circuits thereby permitting the selecting of the relay corresponding to the position of the engineer's valve only during the time interval between code groups and automatically establishing the continuous repeating of the code group as long as the engineer's valve remains in the one position.

In testimony whereof I affix my signature.
